UNITED STATES PATENT OFFICE.

ROBERT COLLINS, OF SAN FRANCISCO, CALIFORNIA.

LINOTYPE-MOUTHPIECE.

No. 797,405.

Specification of Letters Patent.

Patented Aug. 15, 1905.

Application filed July 20, 1904. Serial No. 217,359.

To all whom it may concern:

Be it known that I, ROBERT COLLINS, a citizen of the United States, and a resident of San Francisco, in the county of San Francisco and State of California, have invented a new and Improved Linotype-Mouthpiece, of which the following is a full, clear, and exact description.

The object of the invention is to provide a mouthpiece for the metal pot or crucible of a linotype-machine, by means of which mouthpiece to allow a better flow of metal into the mold and also allow for the thorough venting of the mouthpiece, thus preventing defective slugs. I attain this object by certain novel features of construction, which will be fully set forth hereinafter and pointed out in the claims.

Reference is had to the accompanying drawings, which show as an example a preferred embodiment of the invention, in which drawings like characters of reference indicate like parts throughout the views, and in which—

Figure 1 is a sectional view showing a linotype pot and mold-wheel with my invention applied. Fig. 2 is an enlarged section showing the pot-mouth, the novel mold-piece, the mold, part of the mold-wheel, and a linotype-matrix. Fig. 3 is an enlarged front elevation of the mouth of the pot, showing the mouthpiece in position. Fig. 4 is an enlarged front elevation of the mouthpiece with parts in section, and Fig. 5 is a cross-section on the line 5 5 of Fig. 4.

In Figs. 1, 2, and 3, 10 indicates the pot, having a mouth 10^a. 11 indicates the mold-wheel, 12 the mold, and 14 a linotype-matrix, all of which parts are unaltered by my invention. The mouthpiece 15 lies in the mouth 10^a and is to be secured by any desired means, preferably by beveling the side edges of the mouthpiece and engaging therewith and with the mouth 10^a bevel-keys 16. The mouthpiece is formed with a slot 17 extending continuously through it, except that it is broken at one or more points by bridges 18, which span the slot to strengthen the mouthpiece and prevent warping thereof. The slot 17 is strictly continuous at its front side, the bridges lying at the rear side of the slot, and the arrangement of said bridges is such that they do not interfere with the substantial or practical continuity of the said slot. This slot is adapted to have the metal forced through it into the mold, and by means of said slot a free unobstructed flow of metal is allowed, producing a solid slug and permitting all of the metal re-

quired quickly to flow into the mold. The face of the mouthpiece is formed with a number of vertical grooves 19 extending from the bottom of the mouthpiece upward to a point near the top, where they respectively meet horizontal passages 20, extending rearward into the mouthpiece and communicating with a longitudinal passage 21, which extends through the mouthpiece from end to end thereof. This passage 21 may be formed in any desired manner, but preferably by milling out the rear of the mouthpiece and then closing the passage formed by a plate 22. (See Fig. 5.) The grooves 19 and passages 20 and 21 form effective vents from the face of the mouthpiece to each end thereof and allow all gases to escape from between the mouthpiece and mold, thus avoiding blow-holes and other defects in the slugs. The openings 20 are relatively minute, and their size, while sufficient to carry off the air and gases, as explained hereinbefore, tends to prevent the movement of metal into the passage 21. Should metal pass the openings 20, however, the temperature of the surrounding parts keeps the metal in a fluid state, and as the air and gases blow through the openings 20 and passage 21 they will carry out such metal as may enter the passage, thus keeping it clear and permitting it to serve its purpose effectually.

With the mouthpiece thus constructed not only do I provide for a copious and unobstructed flow of metal into the mold, but I also completely vent off any gases which might otherwise form blow-holes or other defects in the casting, thus allowing for rapid operation of the machine, producing at the same time the most effective slugs.

Various changes in the form, proportions, and minor details of my invention may be resorted to at will without departing from the spirit and scope thereof. Hence I consider myself entitled to all such variations as may lie within the terms of my claims.

Having thus described my invention, I claim as new and desire to secure by Letters Patent—

1. A linotype-mouthpiece having a venting-passage extending longitudinally therein from end to end thereof, and the passage communicating with the front face of the mouthpiece.

2. A linotype-mouthpiece having a venting-passage extending longitudinally through it from end to end, and communicating with the metal-passage in the mouthpiece.

3. A linotype-mouthpiece having a longi-

tudinally-extending venting-passage therein, a transverse opening leading from one side of the mouthpiece to the venting-passage, and a groove formed in said side of the mouthpiece and leading from the metal-passage thereof to the said transverse passage.

4. A linotype-mouthpiece having a slot extending longitudinally therein and forming a metal-passage, a venting-passage extending longitudinally in the mouthpiece, transverse passages passing from the venting-passage to one face of the mouthpiece, and grooves extending from the transverse passages to the said metal-slot.

5. A linotype-mouthpiece having a slot for the passage of the metal, the slot running longitudinally of the mouthpiece and being continuous or unbroken at the front face thereof, and a bridge-piece extending across the slot rearward of its front face for the purpose specified, the mouthpiece also having a venting-passage therein, and means placing said passage in communication with the slot at the front face of the mouthpiece for the purpose specified.

6. A linotype-mouthpiece having a slot for the passage of the metal, the slot running

longitudinally of the mouthpiece and being continuous or unbroken at the front face thereof, and a bridge-piece extending across the slot rearward of its front face, for the purpose specified.

7. A linotype-mouthpiece having an opening therein for the passage of the metal, and also having a venting-passage extending longitudinally in the mouthpiece and open at one end thereof, and a passage extending from the venting-passage to and communicating with the metal-passage at the front face of the mouthpiece.

8. A linotype-mouthpiece having a longitudinally-extending venting-passage therein, a transverse opening leading from the front face of the mouthpiece to the venting-passage, and a groove formed in the front face of the mouthpiece and leading from the metal-passage thereof to the said transverse opening.

In testimony whereof I have signed my name to this specification in the presence of two subscribing witnesses.

ROBERT COLLINS.
